UNITED STATES PATENT OFFICE

CLIFFORD NORTON, OF SOUTH ORANGE, NEW JERSEY, ASSIGNOR TO GRAHAM & NORTON COMPANY, OF NEW YORK, N. Y., A CORPORATION OF DELAWARE

ELEVATOR OPERATING AND CONTROL APPARATUS

Application filed March 18, 1927. Serial No. 176,553.

This invention relates to means for operating elevator doors from the elevator car and for controlling the movement of the car combined and acting in the manner more particularly hereinafter described to prevent the operation of the door by the attendant on the car until after a lock engaging and locking the door operating mechanism is released and a control switch or interlock switch is also operated to prevent the electric or other power from acting to move the elevator.

The invention relates more particularly to an apparatus wherein the door operating mechanism is actuated by pneumatic or other power controlled in its application or action to said door mechanism from the car by a suitable agency thereon and wherein there is also employed a lock for locking said door operating mechanism and a safety interlocking or controlling switch controlling the operation of the elevator motor to prevent the elevator from being moved away from its position at the landing until the catch or lock has been restored to its position for locking the door operating mechanism in the closed position of the door.

In my improved apparatus the door actuating mechanism, a latch or lock therefore and the controlling or interlock switch may all be operated or brought into action by the operation of a single actuating or controlling device but the lock will not be removed to free the door and the application of the power to the door actuating mechanism to open the door will not take place until after the interlock switch comes into effective action.

Further advantages resulting from the combination of apparatus herein described and shown will be obvious to those skilled in the art.

The invention further consists in the special combination of the apparatus herein after more particularly described and then specified in the claims. One of the forms of the apparatus capable of carrying out or effecting the objects above stated and employing my invention is illustrated in the accompanying drawings in which:

Fig. 1 is a front elevation of one form of apparatus embodying my invention.

Fig. 2 is an enlarged side elevation of a part of the same.

Fig. 3 is an edge view of the same.

Figs. 4, 5 and 6 show the arrangement of the valve ports of the control valve employed in controlling the application of pneumatic power to the door operating mechanism.

Referring to the drawings, 1 indicates an elevator well door and 2, 2' toggle arms forming a part of the door operating mechanism, said toggles being pivoted together at 3 and pivotally mounted respectively on the door 1 and upon an arm or bracket of a stanchion or frame at the landing and being adapted and arranged if desired to hold the door against movement when they are in the usual normal position shown. It will be understood that as many of the devices to be hereinafter described upon the landing are employed as there are elevator door openings or floors in the shaft through which the elevator moves. Connected to the toggle 2' is a link or rod 4 capable of lifting the same to break the toggle joint and operate the door to open the same.

4' is a handle for the actuating mechanism adapted to be used for manually operating the same when desired in place of the power agent like air under pressure or electricity. Rod 4 is pivotally connected to the toggle 2' by attachment at one of its ends to a bracket thereof and at its other end to a reciprocating cross-head or other vertically movable member 5 that is tied or mechanically connected to a rod 6 to which motion is imparted by the application of any suitable motive power for the movement of the parts to cause the opening of the door and preferably by a spring for movement in the other direction when the motive power is cut off.

In the present instance I have shown the invention as carried out by the employment of a spring 7 for returning the toggle to its locking position and moving the door back to closed position. I have also shown the invention as carried out by the appli-

cation of pneumatic pressure to a piston 8 connected to rod 6 for opening the door by lifting the toggle 2' but it is to be understood that other motive power agents may 5 be employed and controlled in their application to the door operating mechanism by a valve or similar controlling means as well understood in this art and also that the door may be closed by pneumatic or other 10 power suitably controlled in its action.

In the present instance, pneumatic power being employed to open the door, the rod 6 is tied to the piston 8 of the cylinder 9 and the admission of air or other fluid pressure 15 sure agent beneath said piston is controlled in a suitable way by a valve 10. When pressure is applied the door is opened and upon a relief of pressure under the piston the door is closed by the spring 7 which is 20 compressed by the piston in the door opening operation all as also described in my pending application filed July 7, 1923, Serial #650,044. Other power brought into action for closing the door could be used with- 25 out departing from my invention as for instance in the manner described in my Patent No. 1,578,678, March 30, 1926, issued upon application filed July 7, 1923.

The details as to the ports and connections of the valve 10 which may be employed are shown in Figs. 4, 5 and 6. In these figures 11 indicates the head of the cylinder 9 and 12 a port through which air under pressure may be admitted to or 35 exhausted from the cylinder. The valve is shown as of the disk type, the disk being indicated at 13 and having a port 14 adapted to open and close a connection with the port 12. A port 15 of the disk establishes connection 40 between a port 17 taking air under pressure from a connection 18 and a chamber 19 on one face of the disk valve whence it may pass through ports 14 and 12 to the cylinder 11 when the valve is turned to the 45 position indicated in Fig. 4. 20 indicates an exhaust port which is connected with the port 12 through a chamber 21 on the rear face of the disk valve when said disk valve is in the position shown in Fig. 5 but is 50 disconnected therefrom when the valve is turned to the position indicated in Fig. 4.

From the above it will be apparent that when the valve is turned in the direction of the arrow 22 from position shown in Fig. 5 to position shown in Fig. 4, the air under pressure will pass through ports 18, 15, 14 and 12 into the cylinder 11 and lift the piston thus causing the elevator door to open and the door will retain such open position 60 until the pressure is relieved. When the valve disk is moved back in the direction of the arrow 23 so as to cut off the flow of air under pressure through ports 14 and 12 the port 12 will be placed in connection 65 with the exhaust port and the piston may

drop under the action of the spring or other power and cause the door to close. The disk valve shown is a typical form and the arrangement of ports to cause the application of air pressure and exhaust in the manner described may be accomplished by other structures of air valves.

Means for suitably actuating the valve and the other parts to be hereinafter described from the car may be constructed as 75 follows:

24 is a suitable operating or controlling shoe or cam mounted on the car in a manner to adapt it to be projected laterally by any suitable means of a mechanical or electrical nature so as to cause the various agents herein described to function. Examples of such means are described in my Patents No. 1,550,449, Aug. 18, 1925, issued on application filed Aug. 2, 1923, and No. 1,545,164, July 7, 1925, issued on application filed Jan. 17, 1925. Said shoe is adapted to engage the vertical arm of the bell crank lever 26 thereby raising the horizontal arm of said lever and pushing up the rod 27. Said rod 27 is connected as shown in Fig. 2, to an arm 28 of the disk valve. A spring 29 may be used to assist in returning the valve and connected parts to normal position shown after actuation by the cam. A rod 30 is suitably connected to another arm 30 of the disk valve or to a continuation of the arm 28 so as to be pulled downwardly when the rod 27 is pushed upwardly by the action of the cam 24 or other means.

A suitable latch or lock for the operating mechanism and an electrical lockout or interlocking electric switch such as described in my prior Patent No. 1,550,449, Aug. 28, 1925, issued upon application filed Aug. 8, 1923, are operated from the rod 27 through said rod 31 and associated parts. The latter rod 31 at its upper end is linked up with a lever 32 pivotally mounted if desired on the same pivotal center as the toggle 2'. An arm or extension of the lever 32 engages under a locking arm or catch 33 that in its normal position holds the toggle 2' from lifting, this locking engagement being effected by the shoulder 34 on the latch or lock which is adapted to drop down behind the lug or bar 35 connecting the two sides of the usual split arm of the toggle 2' under the influence of gravity or other influence when the arm of the lever 32 recedes due to lifting of the rod 31. Said rod 31 lifts when the valve arm 28 swings downwardly with the downward movement of rod 27 permitted by the recession of the cam 24. The lifting of the rod 27 due to the action of the shoe or cam 24 and the consequent downward movement of the rod 31 lifts the latch 33, frees the toggle 2', and the action of the valve causes or permits power to be applied, as already explained, to operate the 130

toggle and cause the door to open. During this lifting movement the latch or lock 33 rides on the lug or bar 35.

This movement of the parts under the action of the shoe or cam on the car to unlock the door operating mechanism and apply the power to open the door also imparts movement to the operating member of a hoisting motor control switch or interlocking electric switch that controls a circuit of the hoisting electric motor for the car or its control in a manner to prevent or stop operation of said motor and at all times the toggle arm is freed from the influence of the lock or catch 33. Conversely the control switch cannot restore the circuits to operative condition until the door has been closed and the latch has resumed a position in which the door operating mechanism will be locked by said latch against movement for opening the door. The casing of an interlocking or control switch of suitable character for this purpose is shown at 37. The switch shown comprises essentially two members 38 through which the control or interlock circuit 39 for the hoisting motor is closed when the parts are in the normal position shown in Fig. 1, the door operating mechanism being at such time locked. When the latch or lock 33 has moved upwardly sufficiently to free the door operating mechanism a member of the switch, indicated at 40 and comprising preferably a block of insulating material, is interposed between members 38 and opens the circuit. Movement of member 40 for this purpose is imparted through any desired means co-operating with the lock in its unlocking action, said means comprising, for instance, arm 41 extending from or connected with the lock lever 33 and tied to switch member 40 by a link 42. When the locking lever 33 returns to locking position it pulls down the member 40 and restores the controlling circuit 39 to normal condition thus permitting the car to be moved through the usual motor controlling means employed for that purpose. The recession of member 40 is brought about by the recession of the main control rod 27 which is permitted to drop back when the shoe 24 is permitted to recede by the attendant on the car or by other agency but said member 40 cannot move sufficiently and operate to restore circuit 39 and permit the car to be moved until the latch 33 has been moved sufficiently to engage block 35 and thus lock the toggle bars or other portions of the operating mechanism of the door.

At 43 is shown a pair of dashpot cylinders for checking the movement of the door, these cylinders being suitably tied up to the operating or actuating mechanism of the door and co-operating therewith in a manner which is described in my Patent No. 1,578,678, application filed July 7, 1923. As

this dashpot action forms no part of my present invention the action of said dashpots and the mechanism for operating the same need not be further described.

The general operation of the apparatus is as follows:

The normal position of the parts when there is no car at the landing is shown in the Fig. 1. The cam or shoe 24 is normally in retracted position so that a car may pass a landing at which a stop is not desired without operating the bell crank lever and rod 27 attached thereto. This movement of the car is permitted owing to the fact that the control or interlock switch shown at the top of the figure is in position to permit the hoisting motor and its controlling devices to function in the usual manner. When the car reaches the landing the cam is automatically or manually projected for the purpose of opening the door.

In normal position of the parts and before action of the cam at the landing, the valve ports are in the position indicated in Fig. 5. When, under the action of the cam, the rod 27 rises, it turns the valve and lifts the latch and associated parts but the ports 12 and 14 will not register or open connection for application of the pneumatic power or will not open sufficiently to render the same effective until the latch or lock 33 has freed the door operating mechanism. With the lifting of the latch and as soon as or shortly before the door operating mechanism is freed the member 40 of the interlocking switch opens the circuit 39 thus preventing movement of the elevator. After the lock 33 has been moved sufficiently to free the door operating mechanism, the pneumatic control or valve will have reached position for effectively applying the motive power. The door will then open under the action of the pneumatic power applied to the piston 8 and the spring 7 therein will be compressed and will store power for the closing movement. The continued movement or lifting of the rod 27 and the valve connected therewith will result in moving said valve to the full position shown in Fig. 4 and the door will be held open by the power in the cylinder.

To close the door and permit the restarting of the car the cam 24 and main control rod 27 are permitted to recede and the valve returns to its normal position to open the exhaust and permit the spring to act and reclose the door. In this return movement of the rod the latch or lock is permitted to drop but will not immediately reach its locking position because it will ride on the locking lug or block 35 until said block passes under the edge of the shoulder 34, after which the latch passes to locking position. The electric control or interlock switch 39 will remain in open condition until the member 40 has receded to approximately the position

5 indicated in the full lines of Fig. 2 and said member 40 will not assume said position until after the locking member 33 has moved down to position to engage with and lock the
10 operating mechanism. Therefore it is necessary, as will be seen, that the actuating devices for said door operating mechanism or the controlling valve or other member therefor be restored to position for effecting closure of the door and for effecting a locking of the door in the closed position before the interlocking switch is restored to position for permitting the car to be operated by the elevator hoisting motor.

15 What I claim as my invention is:

1. In an elevator control apparatus, a door, a car relatively movable with respect to the door, toggle arms pivotally connected and adapted in normal position to lock the 20 door against movement, a lock connected to one of said arms, means for releasing said lock, power means operatively associated with said toggle arms for controlling the movement of said door, said means being dependent in its operation upon the previous release of said lock.

2. In an elevator control apparatus in combination, a door, a car relatively movable with respect to the door, means for opening 30 the door comprising an actuating mechanism, a lock engaging said actuating mechanism, a power controlling switch, and a single operating member for said lock and switch for causing first, the opening of said switch, and, subsequently thereto, the release of said lock, whereby the power control for said car is rendered inoperative before the lock is removed from the door.

3. In an elevator control apparatus, a door, a car relatively movable with respect to the door, fluid pressure means for opening the door, a lock for the door, a power controlling switch, and operating mechanism for said lock, switch and fluid pressure means, constructed and arranged to cause first, the opening of said switch, and subsequently thereto, the release of said lock and the operation of said fluid pressure means.

4. In an elevator control apparatus, a door, 40 a car relatively movable with respect to the door, means for opening the door comprising a fluid pressure motor, a valve for controlling the supply of fluid to said motor, a power controlling switch, and operating mechanism for said switch and valve constructed and arranged to complete, first, the opening of said switch and, subsequently thereto, the operation of said valve, whereby the door can be opened only after said switch is opened.

5. In an elevator control apparatus, a door, a car relatively movable with respect to the door, means for opening the door comprising a fluid pressure motor, a power controlling switch, and an operating connec-

tion constructed and arranged to complete, first, the opening of said switch and, subsequently thereto, the operation of said motor, whereby the door can be opened only after said switch is opened.

6. In an elevator control apparatus, a door, a car relatively movable with respect to the door, means for opening the door comprising a fluid pressure motor and operating connections from said motor to the door, a valve for said motor, a car controlling switch, and operating mechanism for said valve and switch constructed and arranged to complete, first, the opening of said switch and, subsequently thereto, the 75 operation of said valve, whereby the door can be opened only after said switch is opened.

7. In an elevator control apparatus, a door, a car relatively movable with respect to the door, toggle arms pivotally connected and adapted in normal position to lock the door against movement, power means associated with said toggle arms for controlling the movement of said door, a power controlling switch, and operating mechanism for said switch and power means constructed and arranged to cause, first, the opening of said switch and, subsequently thereto, the 80 operation of said power means.

8. In an elevator control apparatus the combination with a door, of a car relatively movable with respect to the door, a circuit to the hoisting motor for said car, a switch in said circuit, toggle arms associated with said door to cause movement thereof, a motor for controlling the movement of said toggle arms, and an operating connection for said switch and motor constructed and arranged to cause, first, the opening of said 90 switch, and subsequently thereto, the operation of said motor.

9. In an elevator control apparatus, the combination with a door, of a car relatively movable with respect to the door, a circuit to the hoisting motor for said car, a switch in said circuit, toggle arms pivotally connected and adapted in normal position to lock the door against movement, a lock on one of said arms adapted to lock the toggle 100 system, a motor for controlling the operation of said toggle arms, and a unitary operating mechanism for said switch, lock and motor.

10. In an elevator apparatus, in combination, a door, a car relatively movable with respect to the door, means for opening the door comprising a door actuating mechanism, power means for actuating said mechanism, a locking element including means movable to or from position to lock said actuating mechanism against movement, an elevator hoisting motor control switch, and means on the car for controlling said power means, locking element and switch.

11. In an elevator apparatus, in combination, a movable door, means for moving the door comprising an actuating mechanism, control devices for said actuating mechanism, a lock engageable with said actuating mechanism for preventing movement of the same and means for controlling in one operation said lock and said control devices.

12. In an elevator apparatus, in combination, a movable door, means for moving said door, a lock for said door, a power controlling switch and means for controlling in one operation said door moving means, lock and switch.

15 13. In an elevator apparatus, a movable door, toggle arms pivotally connected and adapted in normal position to lock the door against movement, a lock associated with one of said arms, power means operatively associated with said toggle arms for controlling the movement of said door through said toggle arms and means for controlling said lock and power means.

14. In an elevator apparatus, the combination with a movable door, of a circuit for controlling the hoisting motor for said car, toggle arms pivotally connected and adapted in normal position to lock the door against movement, a lock associated with one of said arms and adapted to lock the toggle system, a motor for controlling the operation of said toggle arms, and an operating mechanism for controlling said circuit, lock and motor.

35 Signed at New York, in the county of New York and State of New York, this 14th day of March A. D. 1927.

CLIFFORD NORTON.
